UNITED STATES PATENT OFFICE

JOSEPH D. KASTER, OF SALEM, OREGON, ASSIGNOR TO OREGON PULP AND PAPER COMPANY, OF SALEM, OREGON

AUTOMATIC FELT WASHER FOR PAPER MACHINES

Application filed June 30, 1931. Serial No. 547,966.

My present invention has reference to improvements in means for automatically washing the felts of paper making machines, and more particularly it is my purpose to provide 5 a felt washer which will automatically move across the under surface of a felt while it is in operation on a paper making machine, to remove dirt, scraps of paper stock, and fine particles. Conventional paper making 10 machines, now in use, take up the particles of paper stock upon an endless moving felt; that is, the newly made wet paper sheet is supported by the felt which in turn passes between two heavy press rolls, the purpose of 15 which is to squeeze the water out of the paper. In operation, the water is squeezed out of the paper and through the felt which, in the course of a very few hours, becomes dirty and matted with fine particles of paper stock. It 20 is practice in the paper industry to run paper making machines continuously for more than one shift and it is a very difficult and complicated operation to stop or shut down a paper making machine so long as stock is being 25 fed to it from the beaters. Accordingly, when a felt becomes dirty and it is necessary to shut down or stop the paper making machine, there is a serious loss in production.

My present invention contemplates the 30 utilization of a suction box or chamber which is movably supported on tracks beneath the endless felt so that the felt will just rub across the top of the box or chamber. The suction box is provided with suction holes, and 35 ahead of each section hole a stream of water is forced against the felt and which is subsequently sucked out of the felt through the suction openings, thereby cleaning the felt of any particles of paper stock or dirt that may 40 be accumulated thereon. In order to prevent cleaning the felt in streaks or spots only, my invention contemplates slowly and continuously moving the suction box back and forth beneath the felt as it passes over the suction 45 box, so that the entire felt is cleaned. It is understood that the operation of my suction cleaning apparatus is continuous throughout the whole time that the paper making machine is in operation so that the felt is automatically kept in a clean condition and it is

never necessary to shut down the paper making machine.

Paper making machines consume a vast quantity of water, which is largely under pressure, and for that reason my automatic 55 felt washer is hydraulically actuated and reversed, and the number of working parts is reduced to a minimum so that the possibility of its becoming out of order or inoperative is largely eliminated and repairs may be 60 quickly and easily executed.

While in the foregoing some of the principal objects and advantages of my invention have been pointed out, it is understood that the scope of my invention should only be determined by reference to the subjoined 65 claims.

In the drawings wherein the preferred form of my invention is illustrated:—

Figure 1 is a plan view of my automatic 70 felt washer assembly.

Figure 2 is an end view thereof, and

Figure 3 is a side elevation thereof.

In the drawings wherein like characters of reference are used to designate like or similar parts throughout the several views:—

The numeral (1) designates my suction box which may be of any suitable construction, and is slidingly supported on rails (2 and 3) or guides, beneath the endless felt, (not shown) of a conventional paper making machine so that the felt passes over and in contact with the top of the box. The suction box (1) is disposed transversely with respect to the felt (not shown) and is of considerably 80 less width than the felt (preferably about 26 inches shorter). The suction box has two (or more) suction holes (4) therein and there is a shower pipe (5) in advance of the box for forcing a stream of water against the felt as 85 it passes over the box, which is then sucked out of the felt, taking accumulated dirt, waste and fine particles of paper stock with it.

The suction box has a suitable connection 90 (6) at one side with the piston rod (7) of a hydraulic power assembly (8). The piston rod (7) passes through a stuffing box (9) into the cylinder (10) into connection with a double-action piston assembly (not shown) therein.

The suction box also has connected therewith a reversing rod (11) which slides in guides (12) and has connection with a lever (12^a) connected with the four way valve (13) of the hydraulic reversing cylinder assembly (14).

Water under pressure, or other suitable means (such for instance as compressed air or the like) is fed through pipe (15) into branch connections (16) and (17), one to the hydraulic power assembly (18) and the other to the hydraulic reversing mechanism (14).

The hydraulic power assembly (8) has a four way operating valve (18) into which the pipe (17) leads, and which is connected with branch pipes (19) and (20) leading to the two heads of cylinder (10).

The hydraulic reversing mechanism (14) also has a four-way valve (13) into which the pipe (16) leads, and which is connected with branch pipes (21 and 22) leading to the two heads of cylinder (23).

Assuming that water is admitted to pipe (15); the valve (18) being set to feed the same through pipe (20) to the forward head of the cylinder (10). The piston rod (7) will be moved back drawing the suction box along with it. The reversing rod (11) is moved back, moving the lever (12^a) to throw the valve (13) to admit water from pipe (22) to the forward head of cylinder (23) which actuates the pistons therein (not shown) to move the piston rod (24) back to draw the lever (25) connected therewith back to throw valve (18) to shut off water from pipe (20) and admit water to pipe (19) to move the piston in the hydraulic power cylinder and its rod (7) forwardly and consequently to move the suction box (1) forwardly. The operation of my invention is accordingly automatic in every respect, and automatically reversing, to move the suction box (1) back and forth beneath the felt so that the entire surface of the felt as it passes over the box is acted upon to completely, automatically, and continuously cleanse the same.

The cylinder (10) and the cylinder (23) are suitably mounted in supports (26) and (27), there is a suction hose connection (28) on the suction box for attaching a suitable flexible suction hose (not shown). There are also suitable supports (not shown) for the guide rails (2 and 3). The views of the drawings are designed to show the operative features of the present invention without including the well-known construction of paper making machines, felts, supports, and the like.

From the foregoing, it is believed, that the construction operation and advantages of my invention will be apparent, but since some changes in detail may be desirable in the detailed parts of its organization, it is again emphasized that interpretation thereof should only be conclusive when made in the light of the subjoined claims.

I claim:

1. In combination with a paper making machine of the type having a continuous, moving felt carrying the wet paper stock, a washer for the felt comprising a suction box located beneath and in contact with the felt and having spray means in conjunction therewith, a hydraulic piston assembly, the piston rod of which is connected with the suction box to move the same beneath the felt, and hydraulic reversing mechanism for the piston assembly and actuated by movement of the suction box for controlling said piston assembly to give a reciprocating motion to the suction box. 70

2. In combination with a paper making machine of the type having a continuous, moving felt carrying the wet paper stock, a washer for the felt comprising a suction box having suction openings therein located beneath and in contact with the felt and having spray means in conjunction therewith and in advance of the suction openings a hydraulic double acting piston assembly, the piston rod of which is connected with the suction box to move the same beneath the felt, and hydraulic reversing mechanism for the piston assembly, and actuated by movement of the suction box for controlling said piston assembly to give a reciprocating motion 80 to the suction box there being a pair of associated four-way valve devices in conjunction therewith. 85

3. In combination with a paper making machine of the type having a continuous moving felt carrying the wet paper stock; a washer for the felt comprising a water spray pipe extending transversely of the felt and beneath the same, a suction box located adjacent said spray pipe and extending transversely of the felt, beneath and in contact with the felt; said suction box having suction openings therein and having a length less than the width of the felt; a frame carrying the suction box; a hydraulic double acting piston assembly, the piston rod being connected with the suction box to move the same beneath the felt, and hydraulic reversing mechanism for the piston assembly including an actuating rod connected to the suction box to be controlled by the movement of the suction box; a common fluid pressure supply pipe having branches to the piston assembly and the reversing mechanism, and four way valves, one for the piston assembly and one for the reversing mechanism, said valves controlling the introduction of fluid under pressure thereto. 100

In testimony whereof I affix my signature hereunto. 105

JOSEPH D. KASTER. 115
